WATER CONTROL IN STEAM GENERATORS

William F. Ryan, Newton, Mass.

Application August 6, 1932. Serial No. 627,726

4 Claims. (Cl. 122—382)

This invention relates to the operation of steam generators and the object is to provide for the maintenance of a suitable quality of water in such generators, avoiding excessive concentration of impurities without excessive loss of water and without excessive loss of heat. For convenience in the following description I will use the short word "boiler" signifying thereby steam generating apparatus or parts thereof in which

10 it is desirable to control the quality of water.

My invention will be well understood by reference to the following description taken in connection with the accompanying drawing, wherein I have shown as an illustrative embodiment 15 of my invention a section, partly broken away, of one form of boiler.

Before proceeding to a detailed description of the particular illustrative example of my invention herein shown, it will be convenient to 20 discuss in a general way the conditions as to water impurities which are encountered in boiler practice, the undesirable effects of which the practice of my present invention minimizes.

The presence of excessive quantities of 25 impurities in the water being evaporated in a steam boiler may cause corrosion of the metal in the boiler; or it may cause the water in the boiler to foam or prime, causing water and impurities to be carried out of the boiler; or it may cause 30 incrustation of solids on the heating surfaces of the boiler and this incrustation may result in loss of thermal efficiency and/or it may result in physical damage to the boiler; or excessive concentration of impurities may cause a combination 35 of any or all of the foregoing difficulties. There is ordinarily a certain amount of impurities in the feed water which is supplied to steam boilers. As the water is evaporated, most of the

40 impurities remain in the unevaporated water, resulting in a concentration of the impurities within the boiler. This concentration will increase indefinitely unless part of the unevaporated water remaining in the boiler is removed, continuously or intermittently, permitting a dilution 45 of the water within the boiler by feeding more water than is actually evaporated. If the feed water supplied to a boiler contains 200 parts per million of impurities and 10% of all the water fed to a boiler is removed from the boiler before it is evaporated, the unevaporated water within the boiler will ultimately become concentrated tenfold, that is, it will contain 2000 p. p. m. of impurities. This process of removing part 50 of the water, with its concentrated impurities, is commonly called "blowing down" the boiler, and

the water removed is commonly called the "blowdown".

The blowing down of water from a boiler results in the loss of water, heat and power. The hot water blown down has to be replaced, usually at considerable expense, because ordinarily the make-up water must be chemically treated, or manufactured by distillation. While means may be adopted to recover heat from blowdowns, it is seldom practicable to recover it all, and usually the recovery of heat from blowdowns prevents or limits heat recovery from other sources which would have a more beneficial effect on the overall efficiency of a power plant. The make-up water, which replaces the blowdown, must be 60 pumped into the boiler at some expense for power. Also, the recovered heat, when this is accomplished, is degraded from the heat level of the boiler and, to that extent, reduced in its 65 capacity for direct conversion into power.

70 The permissible concentration of impurities in feed water depends on many factors, some of which are interrelated. Among these factors are:—

(1) Chemical and physical properties of the 80 impurities;

(2) Quantity of water evaporated, in proportion to:

(a) The area of heating surface in the boiler; 85
(b) The steam relieving area of the boiler;
(c) The steam and water passage areas in the boiler;

(d) The width of the boiler, or, to state the matter more precisely, in proportion to a number of items which are affected by the width of 90 the boiler.

(3) The rate of heat transfer per unit of boiler surface;

(4) The temperature of the boiler metal;

(5) The pressure and temperature of the 95 boiling water.

High concentrations of impurities in boiler feed water are particularly objectionable

(1) When the rate of heat transfer is high; 100
(2) When the boiler metal temperature is high;

(3) When the quantity of steam produced is high:

(a) In proportion to the heating surface of the boiler;

(b) In proportion to the steam relieving area of the boiler;

(c) In proportion to the steam and water passage area of the boiler;

(d) In proportion to the width of the boiler. 110

In the steam generating apparatus adapted to the practice of my invention shown by way of example in the drawing the water-containing parts are all carried in a unitary setting and receive heat from the fire on the grate 3, although such a construction is not essential. The particular construction shown embodies the steam drums 5, 7 and 9 and the bottom drum or mud drum 11 connected to the drums respectively by the sets of water tubes 13, 15 and 17. Suitable portions or baffles 19 cause the hot gases to travel successively past tubes 13, 15 and 17 on their way to the stack at 21. While I have herein shown the lower drum 11 as physically a single cylinder or drum, it is divided by a partition 23 into two separate portions, that on the left hand being connected by tubes 13 and 15 with the drums 5 and 7, the water and steam-containing spaces of which are themselves connected respectively by tubes 25 and 27, these drums 5 and 7 and tubes 13 and 15 and the left hand portion of drum 11 thus constituting a water-containing and circulating system. The right hand portion of drum 11 is connected by tubes 17 to drum 9 which is not in communication with either of the drums 5 and 7 so that these parts form a separate water-containing and circulating system. These two systems are differentially exposed to the heat of the fire as only cooler gases which have traversed the tubes 13 and 15 and lost some of their heat reach the tubes 17. Thus the systems are differentially sensitive to concentration of impurities therein. In other words, in a system which raises steam in drum 9 a higher concentration of impurities is permissible than in a system which raises steam in drums 5 and 7. Herein the two heating systems are operated to deliver steam at the same pressure and I have shown the steam offtake pipes 29 and 31 leading from the drums 5 and 7 respectively connected to a super heater 33 in which the steam is delivered to a steam main 35.

Feed water and make-up water is supplied to the system subjected to the higher heat as, for instance, through pipe 37 to drum 5, while the system subjected to lower heat is supplied from the partly concentrated water in the other section, for example, by drawing it from the left hand section of drum 11 through pipe 39 and delivering it at 41 to drum 9. To permit this to be graphically illustrated I have here shown a connection between these parts exterior to the boiler proper and I have herein shown a pressure-creating means such as a pump 43. In the example illustrated, moreover, I have shown drum 9 at a lower elevation than drums 5 and 7 so that transfer of water might be effected by gravity through by-pass 45, this being an example of transfer of water by a differential pressure created otherwise than by a pressure-boosting mechanism such as a pump. The transfer of water from one water-containing system to the other may be effected continuously or intermittently and controlled either manually or by means of an automatic regulator such as that indicated in 47. Water is evacuated from the complete system by withdrawing it from the less sensitive system, herein that making steam in the drum 9. Otherwise expressed, the final blowdown may be from the right hand portion of drum 11 through valve 49 and may be effected continuously or intermittently in accordance with any of the ordinary methods of blowing down a boiler.

To illustrate the effect of the arrangement described, it should be remembered that with the

ordinary design of boiler all parts are connected so as to form substantially a single circulating system, and if the feed water, for example, contains 200 parts per million of impurities and if the maximum permissible concentration of these impurities in the hotter and more active parts of the boiler is 2000 p. p. m., although a concentration of 4000 p. p. m. might be permissible in the cooler and less active parts of the boiler, then it will be necessary to blow down 10% of the water fed to the boiler, and all parts of the boiler, most active and least active, will contain water having approximately the same concentration of impurities, for example, 2000 p. p. m. If, due to the particular arrangement of the boiler, concentration of the impurities is not substantially uniform in all parts, the higher concentration may occur in those parts where higher concentration is most objectionable.

Now, with such an arrangement as is exemplified by the apparatus shown in the drawing, if the two water-containing systems are so proportioned that about 80% of the steam is generated in the more sensitive system (that making steam in drums 5 and 7) and about 20% in the less sensitive system (that making steam in drum 9) and the total feed supply for the latter is taken from the former, then about 25% of the total feed may pass from the former system to the latter, from 39 to 41, and approximately 5% of the total feed may be finally evacuated or blown down in the latter system at 49. Since 25% of the total feed will be, as it were, blown down from the more sensitive system, the concentration in that system will be only about fourfold; that is, the concentration of impurities will be only 800 p. p. m., providing a greatly improved operating condition as compared with 2000 p. p. m. obtained with 10% blowdown and a boiler of ordinary design. The less sensitive system, herein making steam in drum 9, will be fed with water containing 800 p. p. m. of impurities, but since 20% of the feed in that system, that is, 5% of the original feed herein delivered to drum 5, will be finally blown down at 49, the impurities will not be concentrated beyond the 4000 p. p. m. which is permissible in the cooler and less active parts of the generating system as a whole. Therefore, in the hypothetical case chosen for illustration the practice of the invention not only improves operating conditions in the more active parts of the boiler but reduces by half the loss of heat and water due to blowing down.

The relative steam generating capacity of the two sections of the boiler may have little effect on the quantity of the final blowdown, but any increase in the relative steam generating capacity of the section of lower sensitivity will call for a corresponding increase in the transfer of water thereto from the system of higher sensitivity and so cause lesser concentration of impurities in that system. For any given water conditions the heating surfaces can be proportioned and arranged so that, within obvious limits, any desired concentration of impurities may be obtained in the more sensitive parts of the system.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

150

1. The method of operating steam generators which comprises maintaining desired water levels therein by a serial transfer of water from a location of relatively high sensitivity to water impurities to a location of relatively low sensitivity and evacuating from the latter location such portion of the water as is required to maintain predetermined permissible concentrations of impurities in the several locations. 80
- 10 2. The method of steam generation which comprises establishing in combination with means for heating the same substantially independent water-containing systems such that the sensitivity thereof to concentration of water impurities substantially differs, supplying the water which is to be evaporated to the system of higher sensitivity, supplying water to the system of lower sensitivity from the system of higher sensitivity and effecting at least substantially all the blow-down for both systems required to maintain predetermined permissible concentrations therein entirely from the system of lower sensitivity. 85
- 15 3. The method of steam generation which comprises differentially heating substantially independent water-containing systems for generation of steam therefor at the same pressure, supplying the water which is to be evaporated to a system subject to higher heat, transferring water therefrom to a system subject to lower heat and evacuating from the latter system water as required to maintain permissible concentrations of impurities in the systems. 90
- 20 4. The method of obviating in steam generating plants difficulties due to concentration of water impurities which comprises maintaining desired water levels by transfer of water serially from a relatively highly heated sub-division thereof to a relatively low heated sub-division and blowing down the plant by evacuation from the latter subdivision of water in amount as required to maintain predetermined permissible concentrations of impurities in the subdivisions. 95
